AUTOMATIC IGNITION AND CONTROL
MECHANISM FOR GAS BURNERS

Charles M. Mayer and Samuel T. Craig, Mansfield, Ohio, assignors to The Tappan Stove Company, Mansfield, Ohio, a corporation of Ohio

Application April 12, 1949, Serial No. 86,932

8 Claims. (Cl. 158—135)

1

This invention relates to an automatic ignition and control mechanism for a cooking range burner using gaseous fuel. It is especially adapted for use with the oven burners of cooking ranges, and may be used in conjunction with a time control mechanism or independently thereof as desired.

Our improved mechanism includes a pilot burner, using gaseous fuel, by which the main burner is ignited, an electrical ignition element by which the pilot burner is ignited and a master switch which when closed renders the mechanism operative. The master switch is operatively connected to the main gas control valve in such a manner that it is closed by the opening of the control valve and is opened, rendering the mechanism inoperative, by the closing of the control valve. Thus, to ignite the main burner it is only necessary to open the main control valve. The opening of the control valve closes the master switch which energizes the electrical ignition element. The ignition element then ignites the pilot burner and it in turn ignites the main burner. When the mechanism is used in conjunction with a time control mechanism the main burner is ignited and extinguished, after the control valve has been opened and the master switch closed, according to the setting of the time control mechanism.

It has been found by experience that both the pilot burner and the main burner are sometimes extinguished while the supply of gas thereto is still turned on by the main control valve. This is due to various reasons. Sometimes it is due to the momentary failure of the gas supply or to the slamming of the oven door, and other reasons. The extinguishment of both the main burner and the pilot burner while the gas supply thereto is still turned on causes an accumulation of unburned gas in the oven which frequently explodes when it is endeavored to re-ignite the burners.

In order to prevent any accumulation of unburned gas and thus eliminate any danger of an explosion therefrom in the event the pilot burner and main burner are extinguished for any reason while the supply of gas thereto is still turned on, we provide in our improved apparatus safety control mechanism by which the supply of gas to both the pilot burner and the main burner is completely shut off automatically in the event the burners become extinguished for any reason while the main gas control valve is open. We also provide mechanism which automatically shuts off the supply of gas to both the main burner and the pilot burner in the event of a current failure and in case the electrical ignition element becomes inoperative for any reason.

2

This safety control mechanism comprises a normally closed safety control valve in the main gas supply conduit between the main control valve and the main burner; a normally closed solenoid operated valve in a branch conduit between the main gas supply conduit and the pilot burner through which gas is supplied to the pilot burner; a pair of thermostatic elements both of which are adapted to be heated by the pilot burner when ignited, and one of which is adapted to be heated by both the pilot burner and the electrical ignition element; and a pair of switches, one of which is adapted to be maintained closed by one of said thermostatic elements while heated and the other of which is adapted to be maintained open by the other of said thermostatic elements while it is heated.

In operation the electrical ignition element is energized when the master switch is closed by the opening of the main gas control valve. The electrical ignition element then heats one of the thermostatic elements which after it is heated closes the normally open switch and maintains it closed as long as the thermostatic element is heated. The closing of this switch energizes the solenoid which opens and maintains open the solenoid operated valve in the branch supply conduit thus supplying gas to the pilot burner where it is ignited by the electrical ignition element. The pilot burner then heats both thermostatic elements. After the second thermostatic element is heated it opens, and maintains open while heated the safety control valve and the normally closed switch. The opening of the safety control valve admits gas to the main burner and the opening of the normally closed switch de-energizes the electrical ignition element. After the electrical ignition element has been de-energized the pilot burner maintains both thermostatic elements heated until the main control valve is closed to shut off the gas unless the pilot burner and main burner become extinguished for some reason before the main control valve is closed.

In the event the pilot burner and main burner are extinguished while the main control valve is still open both the thermostatic elements will immediately cool which will open the normally open switch, close the normally closed switch, and close the safety control valve. The opening of the normally open switch will de-energize the solenoid and shut off the supply of gas to the pilot burner, and the closing of the safety control valve will shut off the supply of gas to the main burner. The closing of the normally closed switch will again energize the electrical ignition element so

that it is in condition to heat one of the thermostatic elements in order to close the normally open switch which will cause the solenoid-operated valve to open and again supply gas to the pilot burner where it is ignited by the electrical ignition element. The cycle then continues as described.

In the event of a current failure or in case the electrical ignition element is rendered inoperative for any reason, the thermostatic elements cannot be heated, in which case the supply of gas to both the main burner and the pilot burner will be maintained shut off by the safety control valve and the solenoid-operated valve.

The principal object of the invention is to provide an improved electrical ignition system for gas burners.

Another object of the invention is to provide in an electrical ignition system for a gas burner automatic means for completely shutting off the supply of gas to the pilot and main burners in the event they become extinguished for any reason before the supply of gas thereto is cut off by the main gas control valve.

Still another object of the invention is to provide in an electrical ignition system for a gas burner automatic means for completely shutting off the supply of gas to the pilot and main burners in the event of a current failure or in case the electrical ignition element is rendered inoperative for any reason while the main gas control valve is open.

Other and more limited objects of the invention will be apparent from the following specification and the accompanying drawings forming a part thereof, wherein:

Fig. 1 is a diagrammatic view illustrating our improved electric ignition and safety control mechanism;

Fig. 2 is a plan view of the thermostatic control unit showing the various parts thereof in the position they assume during the time the burner is turned off;

Fig. 3 is a view similar to Fig. 2 showing the various parts in the position they assume just after the gas has been turned on by the main control valve and the master switch closed;

Fig. 4 is a view similar to Fig. 2 showing the parts in the position they assume during the normal operation of the burner;

Fig. 5 is a side elevation of the control unit;

Fig. 6 is a central longitudinal section through the control unit, the plane of the section being indicated by the line 6—6 on Fig. 2;

Fig. 7 is an end elevation looking towards the righthand end of Fig. 2;

Fig. 8 is an end elevation looking towards the lefthand end of Fig. 2;

Fig. 9 is a transverse section taken on the line 9—9 of Fig. 2;

Fig. 10 is a perspective view of one of the thermostatic elements; and

Fig. 11 is a wiring diagram showing the electrical connections of our apparatus.

Referring now to the drawings by reference characters, the numeral 1 indicates a burner using gaseous fuel which is disposed in or in operative relation to an oven 2, one side-wall of which is indicated at 3. Gas is supplied to the burner 1 from a gas manifold 4 through a conduit 5. The supply of gas is controlled by a main control valve 6. When the valve 6 is open, gas will flow from the manifold 4 through the valve 6 and into the conduit 5. A thermostatically operated temperature control valve 7 is inter-

posed in the line 5. This temperature control valve 7 may be set to maintain the oven at any desired temperature and it is controlled by a thermostatic element 8 which is disposed within the oven 2. The temperature regulator valve 7 may be of any desired standard type. Various different thermostatic control valves are available, any one of which will work equally well. Consequently this valve is not shown in detail herein. The valve 7 is set to the desired temperature by an operating handle 7a. Between the temperature control valve 7 and the burner 1 is interposed a normally closed safety valve 9. The valve 9 comprises a casing 10 in which is mounted a ball 11 which is normally held against a seat 12 by a spring 13. The main burner 1 is adapted to be ignited by a pilot burner 14 to which gas is supplied through a branch conduit 15 which is connected to the main conduit 5 through a passage within the temperature control valve 7. If desired the branch conduit 15 may be connected to the main supply conduit 5 between the main control valve 6 and the temperature control valve 7. In the branch conduit 15 we provide a normally closed valve 16 which is disposed between the pilot burner 14 and the junction of the branch conduit 15 with the main supply conduit 5. The valve 16 is adapted to be opened and maintained opened by a solenoid 17.

Adjacent to main control valve 6 we dispose a master switch 18 which is adapted to be opened and closed by suitable connections 19 which are operated by the operating handle 20 of valve 6 as the valve 6 is opened and closed. These connections are such that when the valve 6 is opened to supply gas to the conduit 5 the switch 18 will be closed and when the valve 6 is closed the switch 18 will be opened.

After the gas has been turned on by opening the main control valve 6 and closing the master switch 18, the operation of the device is automatically controlled by a control unit 21. The control unit 21 comprises a frame 22 on which are mounted two thermostatic elements indicated at 23 and 24 respectively. The frame 22 includes a base 25 having opening 26 therethrough adjacent the inner end thereof. The frame 22 extends through an opening 27 in the oven wall 3 and is held in position by a bracket 28. The thermostatic elements 23 and 24 are anchored to the inner upturned end 29 of the frame 21 by screws 30 and 31 respectively. The thermostatic elements 23 and 24 are disposed above the base 25, as clearly shown in Figs. 6 to 9 inclusive, and extend out through the opening 27 in the oven wall 3. Each of the thermostatic elements 23 and 24 has an elongated opening 34 therethrough adjacent the anchored ends thereof and an upturned flange 35 at the other ends thereof. The outer ends of the thermostatic elements terminate adjacent a block 36 of insulating material. The block 36 rests upon a slab of insulating material 37 and is secured to the base 25 by suitable screws 38. The block 36 has secured thereto one contact 39 of a switch 40. The other contact 41 of the switch 40 is carried by the upturned flange 35 of the thermostatic element 23. A switch 42 is secured to the upturned side 43 of the frame 22. The switch 42 comprises a contact 44 secured to a terminal 45 which is secured to the side 43, and a contact 46 which is secured to the outer end of a spring arm 47, the other end of which is suitably secured to a terminal 48, also carried by the upturned side 43 of the frame 22. The ter-

minials 45 and 48 are suitably insulated from the base 22, as indicated at 49. The switch 40 is normally closed and the switch 42 is normally open when the burner is not operating, as indicated in Figs. 1 and 2. The inner anchored ends of the thermostatic elements 23 and 24 are disposed above the opening 26 through the base 25. An insulating terminal block 50 is carried by the base 25 and extends down through the opening 26. Block 50 has secured thereto a pair of terminals 51 and 52 respectively. These terminals extend through the block 50 and support therebetween a resistance coil 53 which acts as an electrical ignition element. The terminal 51 is connected to the terminal 39 by a conductor 54. The pilot burner 14 is disposed below the opening 26 and between the thermostatic elements 23 and 24 in position to project a flame upward through the opening 26 to heat the thermostatic elements 23 and 24 when the pilot burner is ignited. The pilot burner 14 is also disposed in position to ignite the burner 1 after gas has been applied thereto. The ignition element 53 is mounted below the anchored inner end of the thermostatic element 24 and to one side of the pilot burner 14, in position to ignite the pilot burner 14 after it has been energized and gas is supplied to the pilot burner 14. The safety control valve 9 is connected to the frame 21 by a hollow tube 55. A rod 56 which has one end rigidly secured to the upstanding flange 35 of the thermostatic element 23, as indicated at 57, extends through the hollow tube 55 and into the valve casing 10 in position to unseat the ball 11 from the valve seat 12. By this construction and arrangement of the control unit 21 we are enabled to locate the switches 40 and 42 on the outside of the oven where they will not be subjected to the high temperatures of the oven and consequently will function better and will be less likely to get out of order.

Referring now to Fig. 11, the numeral 60 indicates a transformer having a primary winding 61 and two secondary windings 62 and 63 respectively. One end of the primary winding 61 is connected to the line by wire 63 and the other end thereof is connected to the other side of the line by a line 64. The master switch 18 is disposed in the line 64. As shown in Fig. 11, a time control mechanism 65 is provided so that the mechanism may be set for automatic operation when desired. The time control mechanism is electrically operated and may be of any standard construction. Many such devices are available, any of which will work equally well herein. Consequently the specific construction of the time control mechanism 65 is not shown herein. This mechanism is connected to the line by the wires 66 and 67 respectively. A switch 68 is also provided in the line 64 in series with the switch 18. When the apparatus is used without the time control mechanism the switch is in a position shown by full lines in Fig. 11, and when it is desired to use the apparatus in conjunction with the time control the switch 68 is moved to the position shown in dotted lines. This switch 68 is incorporated in the time control mechanism so that when the time control mechanism is set the switch is moved thereby to the dotted line position. When the time control mechanism is used it operates a switch 69. The time control mechanism may be set to turn the burner on at a predetermined time and then turn it off at some later predetermined time. This is done through the switch 69, construction being such that the time control mechanism will close the switch

69 at the time it is set to ignite the burner 1, and will open the switch 69 at the time it is set to turn off the burner.

When the mechanism is used without the time control, current will flow from the line through the lead 63 to one side of the primary winding 61 and then from the other end of the primary winding back to the line through the wire 64 and switches 68 and 18. When the time control mechanism is in use, current will flow from the line through the wire 63 to the primary winding 61 and then back to the line through the wire 70, switch 69, wire 71, switches 68 and 18 and then through the wire 64.

When the primary winding 61 is energized the secondary windings 62 and 63 will also be energized when the switches 40 and 42 are closed. The secondary winding 63 which has one end thereof grounded, as indicated at 72, is wound to produce a 10-volt current and the secondary winding 62 is wound to produce a 25-volt current. When the switch 40 is closed the ignition element 53 will be energized and when the switch 42 is closed the solenoid 17 will be energized and open the valve 16.

The operation of the device will now be described in connection with both manual and automatic operation. Assuming first that the mechanism is set for manual operation. In order to initiate operation the main control valve 6 is opened by the handle 20. The opening of this valve will simultaneously close the master switch 18. Gas is then admitted to the conduit 5 and to the branch conduit 15. However, the gas cannot reach the main burner 1 and the pilot burner 14 until the valve 16 in the branch conduit 15 has been opened and the safety control valve 9 in the main supply conduit 5 has been opened. The closing of the master switch 18 energizes the electrical ignition element 53 since the switch 40 is closed. Current flows from one side of the secondary winding 63 through the ignition element 53 and switch 40 to the ground. The energizing of the ignition element 53 heats the thermostatic element 24. The heating of the element 24 causes it to move from the position shown in Fig. 2 to the position shown in Fig. 3, closing the switch 42. The closing of the switch 42 energizes the solenoid 17, which opens the valve 16. Gas then flows to the pilot burner 14, where it is ignited by the ignition element 53. The pilot burner, after being ignited, heats both the thermostatic element 23 and the thermostatic element 24. The heating of the thermostatic element 23 causes it to move from the position shown in Fig. 2 to the position shown in Fig. 4. This opens the switch 40, thus de-energizing the ignition element 53. However, the thermostatic element 24 is maintained heated by the pilot light 14, after the electric ignition element 53 has been de-energized. Simultaneously with the opening of the switch 42 the thermostatic element 23 opens the valve 9 by unseating the ball 11. Gas then flows to the main supply conduit 5 to the burner 1, where it is ignited by the pilot light 14. As long as the valve 6 is open and the apparatus is operating normally, the thermostatic elements will be maintained in the position shown in Fig. 4 by heat from the pilot burner 14. If for any cause the pilot burner 14 and the main burner 1 are extinguished before the main control valve 6 is closed, the thermostatic elements 23 and 24 will cool and return to the position as shown in Fig. 2, closing the switch 40 and opening the switch

42. The closing of the switch 40 will again energize the electric ignition element 53. This will then heat the thermostatic element 24 and close the switch 42, which will again open the valve 16 and supply gas to the pilot burner 14, provided gas is available. If the burners 1 and 14 have been extinguished, due to a gas failure, the electric ignition element 53 will remain energized until gas is again supplied to the pilot burner 14, where it will be ignited, after which the electric ignition element 53 will be de-energized and the safety control valve 9 opened. From this it will be seen that it will be impossible to supply gas to the main burner 1 unless the pilot burner 14 is ignited so that it can ignite the main burner 1 as soon as gas is again supplied thereto. It will also be seen that it is impossible to initially supply gas to the pilot burner 14 unless the electrical ignition element 53 is energized, as otherwise the valve 16 will be closed.

In the event of a current failure during operation, the solenoid 17 will be de-energized and cut off the supply of gas to the pilot burner 14. Thermostatic element 23 will then cool and allow the spring 13 to close the valve 9 by forcing the ball 11 against the seat 12. It will also be seen that if during operation the electrical ignition element 53 should get out of order and then the main burner 1 and pilot burner 14 become extinguished it will be impossible for the apparatus to again function until the electrical ignition element 53 has again been put in serviceable condition.

When the time control mechanism 65 is used the mechanism will function as above described as long as the switches 18 and 69 are closed.

From the foregoing it will be apparent to those skilled in this art that we have provided a very simple and efficient apparatus for accomplishing the objects of our invention.

It is to be understood that we are not limited to the specific construction shown and described herein, as various modifications may be made thereto within the scope of the appended claims.

We claim:

1. In an automatic ignition and control mechanism of the character described the combination of a gas burner, a supply conduit through which gas is supplied to said burner, a main control valve operative to control the admission of gas into said supply conduit, a normally closed safety valve in said supply conduit between said burner and said main control valve, a pilot burner disposed in position to ignite said burner, a branch conduit through which gas is supplied to said pilot burner, said branch conduit being connected to said supply conduit between said safety valve and said main control valve, a normally closed pilot burner control valve in said branch conduit, a solenoid operative when energized to maintain said pilot burner control valve open, a first thermostatic element, a second thermostatic element, said first thermostatic element and said second thermostatic element being mounted in position to be heated by said pilot burner, an electric ignition element operative when energized to ignite said pilot burner and to heat said first thermostatic element, an operative connection between said second thermostatic element and said safety valve through which said safety valve is maintained open while said second thermostatic element is heated, a normally open switch, an operative connection between said first thermostatic element and said

switch through which said switch is maintained closed by said first thermostatic element while said thermostatic element is heated, a normally closed second switch, an operative connection between said second thermostatic element and said second switch through which said second switch is maintained open by said second thermostatic element while second thermostatic element is heated, said normally open switch being operative when closed to energize said solenoid to open said pilot burner control valve to supply gas to said pilot burner, said normally closed second switch being operative when open to de-energize said electric ignition element, a main control switch operative when closed to render said mechanism operative, and operative connections between said main control switch and said main control valve through which said main control switch is closed by the opening of said main control valve.

2. In an automatic ignition and control mechanism of the character described the combination of a gas burner, a supply conduit through which gas is supplied to said burner, a main control valve operative to control the admission of gas into said supply conduit, a normally closed safety valve in said supply conduit between said burner and said main control valve, a pilot burner disposed in position to ignite said burner, a branch conduit through which gas is supplied to said pilot burner, said branch conduit being connected to said supply conduit between said safety valve and said main control valve, a normally closed pilot burner control valve in said branch conduit, a solenoid operative when energized to maintain said pilot burner control valve open, an electric ignition element operative when energized to ignite said pilot burner, a normally open switch, a normally closed second switch, a main control switch, an electric circuit including said solenoid, said electric ignition element and said switches, a first thermostatic element mounted in position to be heated by said electric ignition element and by said pilot burner, a second thermostatic element mounted in position to be heated by said pilot burner, operative connections between said first thermostatic element and said normally open switch through which said switch is maintained closed by said thermostatic element while said thermostatic element is heated, said switch being operative when closed to energize said solenoid to open said pilot burner control valve and supply gas to said pilot burner, operative connections between said second thermostatic element and said safety valve through which said safety valve is maintained open by said second thermostat to supply gas to said burner while said second thermostat is heated and operative connections between said second thermostatic element and said second switch through which said second switch is maintained open by said second thermostat while said second thermostat is heated, said second switch being operative when open to de-energize said electric ignition element, and said main control switch being operative when closed to render said mechanism operative.

3. In an automatic ignition and control mechanism of the character described the combination of a gas burner, a supply conduit through which gas is supplied to said burner, a main control valve operative to control the admission of gas into said supply conduit, a normally closed safety valve in said supply conduit between said burner and said main control valve, a pilot burn-

9.

er disposed in position to ignite said burner, a branch conduit through which gas is supplied to said pilot burner, said branch conduit being connected to said supply conduit between said safety valve and said main control valve, a normally closed pilot burner control valve in said branch conduit, a solenoid operative when energized to maintain said pilot burner control valve open, an electric ignition element operative when energized to ignite said pilot burner, a normally open switch, a normally closed second switch, a main control switch operative when closed to render said mechanism operative, a transformer having a primary winding and two secondary windings, an electric circuit including said primary winding and said main control switch, a second electric circuit including one of said secondary windings said solenoid and said normally open switch, a third electric circuit including said electric ignition element and said normally closed second switch and the other of said secondary windings, a first thermostatic element adapted to be heated by said electric ignition element and said pilot burner and operative when heated to maintain said normally open switch closed to energize said solenoid and supply gas to said pilot burner, a second thermostatic element adapted to be heated by said pilot burner and operative when heated to maintain said normally closed second switch open to de-energize said electric ignition element and to maintain said safety valve open to supply gas to said burner.

4. In an automatic ignition and control mechanism of the character described the combination of a gas burner, a supply conduit through which gas is supplied to said burner, a main control valve operative to control the admission of gas into said supply conduit, a normally closed safety valve in said supply conduit between said burner and said main control valve, a pilot burner disposed in position to ignite said burner, a branch conduit through which gas is supplied to said pilot burner, said branch conduit being connected to said supply conduit between said safety valve and said main control valve, a normally closed pilot burner control valve in said branch conduit, a solenoid operative when energized to maintain said pilot burner control valve open, an electric ignition element operative when energized to ignite said pilot burner, a normally open switch, a normally closed second switch, a main control switch, a second control switch adapted to be opened and closed by a time control mechanism, said main control switch and said second control switch being operative when both are closed to render said mechanism operative, a transformer having a primary winding and two secondary windings, an electric circuit including said primary winding said main control switch and said second control switch, a second electric circuit including one of said secondary windings said solenoid and said normally open switch, a third electric circuit including said electric ignition element and said normally closed second switch and the other of said secondary windings, a first thermostatic element adapted to be heated by said electric ignition element and said pilot burner and operative when heated to maintain said normally open switch closed to energize said solenoid and supply gas to said pilot burner, a second thermostatic element adapted to be heated by said pilot burner and operative when heated to maintain said normally closed second switch open to de-energize said electric ignition element

10

and to maintain said safety valve open to supply gas to said burner.

5. An automatic ignition and control mechanism of the character described the combination of an oven burner using gaseous fuel, a pilot burner operative to ignite said oven burner, an electric ignition element operative when energized to ignite said pilot burner, a first thermostatic element adapted to be heated by said electric ignition element, and a second thermostatic element, said pilot burner being mounted in position to project a flame against and maintain both said first thermostatic element and said second thermostatic element heated during operation, means including said first thermostatic element operative to control the supply of gas to said pilot burner, and means including said second thermostatic element operative to control the energization of said electric ignition element and to control the supply of gas to said oven burner, said second mentioned means being independent of said first mentioned means.

25. An automatic ignition and control mechanism of the character described the combination of a cooking range oven, an oven burner using gaseous fuel, a pilot burner disposed adjacent said oven burner within said oven and operative to ignite said oven burner, an electric ignition element disposed adjacent said pilot burner and operative when energized to ignite said pilot burner, a first thermostatic element having one end thereof disposed within said oven in position to be heated by said electric ignition element and having the other end thereof projecting out through an opening in the oven wall, a second thermostatic element having one end thereof disposed within said oven and the other end thereof projecting out through said opening in the oven wall, said pilot burner being mounted within said oven in position to project a flame against and maintain both said first thermostatic element and said second thermostatic element heated during operation, means controlling the supply of fuel to said pilot burner operatively connected to the projecting end of said first thermostatic element, and means controlling the supply of fuel to said oven burner and the energization of said electric ignition element operatively connected to the projecting end of said second thermostatic element, said second mentioned means being independent of said first mentioned means.

30. An automatic ignition and control mechanism of the character described the combination of a cooking range oven, an oven burner using gaseous fuel, a pair of spaced substantially parallel thermostatic elements, each of said thermostatic elements having one end thereof anchored within said oven and the other end thereof projecting out through an opening in the oven wall, a pilot burner disposed in position to ignite said oven burner and to project a flame against and maintain both of said thermostatic elements heated near the anchored ends thereof during operation, an electric ignition element operative when energized to ignite said pilot burner and to heat one of said thermostatic elements near the anchored end thereof, means controlling the supply of fuel to said pilot burner operatively connected to the projecting end of one of said thermostatic elements, and means controlling the supply of fuel to said oven burner and the energization of said electric ignition element operatively connected to the projecting end of the other of said thermostatic elements, said second men-

11

tioned means being independent of said first mentioned means.

8. In an automatic ignition and control mechanism of the character described the combination of an oven burner using gaseous fuel, a pilot burner operative to ignite said oven burner and a control unit by which the operation of said burner is controlled, said control unit comprising; a frame adapted to extend into an oven through an opening in one wall thereof, a pair of spaced substantially parallel thermostatic elements disposed above the base of said frame, each of said thermostatic elements having one end thereof rigidly secured to the inner end of said frame and the other end thereof disposed adjacent the outer end of said frame, an opening through the base of said frame beneath said thermostatic elements adjacent the inner end of said frame through which said pilot burner is adapted to project a flame to heat said thermostatic elements, an electrical resistance coil suitably supported by said frame beneath the opening through the base of said frame in position to heat one of said thermostatic elements, said coil also

10 5

12

being operative to ignite the pilot burner, a normally open switch carried by outer end of said frame and adapted to be maintained closed by one of said thermostatic elements when said element is heated, and a normally closed second switch comprising a pair of contacts, one of said contacts being suitably secured to said frame and the other of said contacts being secured to the outer end of the other of said thermostatic elements.
